UNITED STATES PATENT OFFICE.

JOSEPH B. BANNON, OF GRAWN, MICHIGAN.

CLASP FOR SPECTACLE-CASES.

1,245,423.

Specification of Letters Patent.

Patented Nov. 6, 1917.

Application filed March 8, 1917. Serial No. 152,096.

To all whom it may concern:

Be it known that I, JOSEPH B. BANNON, a citizen of the United States, residing at Grawn, in the county of Grand Traverse and State of Michigan, have invented a new and useful Clasp for Spectacle-Cases, of which the following is a specification.

The device forming the subject matter of this application is a clasp for a spectacle case, 10 and the invention aims to provide novel means whereby the lid of the case may be held closed, and whereby the case may be supported on a garment, the garment-engaging element constituting means whereby 15 the lever may be tilted to permit an opening of the case.

It is within the province of the disclosure to improve generally and to enhance the utility of devices of that type to which the 20 present invention appertains.

With the above and other objects in view which will appear as the description proceeds, the invention resides in the combination and arrangement of parts and in the 25 details of construction hereinafter described and claimed, it being understood that changes in the precise embodiment of the invention herein disclosed can be made within the scope of what is claimed, without departing from the spirit of the invention.

Figure 1 shows in front elevation, a spectacle case embodying the invention;

Fig. 2 is a rear elevation of the spectacle case;

Fig. 3 is a side elevation wherein parts are broken away;

Fig. 4 is a cross section on the line 4—4 of Fig. 3; and

Fig. 5 is a fragmental section showing a 40 modified form of the invention.

In carrying out the present invention there is provided a spectacle case which may be shaped as desired. The case comprises as coöperating parts, a body 1 and a lid 2 hinged at 3 to the body. In one of said coöperating elements, preferably the body 1, there is an exterior pivot element 4 on which a lever 5 is mounted, intermediate its ends, for swinging movement in a plane parallel 50 to the bottom of the body 1 of the case. At one end, the lever 5 is provided with a spring hook 6, the bill of which overhangs the lid 2 to hold the lid closed. The bill of the hook terminates in an enlargement 55 7 adapted to be received in a seat 8 in the outer face of the lid 2, to hold the lever

against swinging movement. The other end of the lever 5 terminates in a hook 9, the lower end of which is constructed as shown at 10, so that the hook 9 may be engaged readily with the upper end of a pocket, with a belt or the like, to support the case. The hooks 6 and 9 project in opposite directions, and the finger of the operator may be placed against the hook 9 to swing the lever 5 on the pivot element 4 thereby to disengage the bill of the hook 6 from the lid 2. The pivot element 4 is located above the center of mass of the spectacle case, and the portion of the lever which carries the hook 9 is shorter than the portion of the lever which carries the hook 6. Owing to the location of the pivot element 4 with respect to the ends of the case, as above described, the weight of the case has no tendency to cause the case to swing on the pivot element 4 and disengage the hook 6 from the lid 2 when the device is supported on a belt or on the edge of a pocket by means of the hook 9.

In Fig. 5 of the drawings the body of the 80 spectacle case is denoted by the numeral 1* and the lever is shown at 5*, the numeral 4* denoting the rivet which constitutes a fulcrum for the lever. In this form of the invention, the rivet 4* is provided with a spacing shoulder 20, which, being interposed between the lever 5* and the body 1*, prevents the lever from chafing or wearing the body when the lever is swung.

Having thus described the invention, what 90 is claimed is:—

1. A pocket case comprising as coöperating parts, a body and a lid hinged to the body; and a lever fulcrumed on one of said coöperating parts for swinging movement 95 in a plane parallel to the bottom of the case, the lever being provided at one end with a hook the bill of which overlaps the other of said coöperating parts to hold the lid closed, the lever being adapted to swing parallel to the bottom of the case to disengage the bill of the hook from that coöperating element wherewith the bill coats, the lever being provided with garment-engaging supporting means.

2. A pocket case comprising as coöperating parts, a body and a lid hinged to the body; a lever fulcrumed intermediate its ends on one of said coöperating parts for swinging movement in a plane parallel to 100 the bottom of the case, the lever being provided at one end with a hook the bill of

which overlaps the other of said offset co-operating parts to hold the lid closed, the lever being adapted to swing parallel to the bottom of the case to displace the bill of the hook from that co-operating element where-with the bill engages, the other end of the lever being provided with a pocket-engaging supporting hook constituting means where-by digital pressure may be applied to the lever to swing the same, and to disengage

the bill of the hook from that co-operating element wherewith the bill coacts.

In testimony that I claim the foregoing as my own, I have hereto affixed my signature in the presence of two witnesses:

JOSEPH B. BANNON.
